US00D574688S

(12) **United States Design Patent**
Yamamoto

(10) **Patent No.:** **US D574,688 S**
(45) **Date of Patent:** **** Aug. 12, 2008**

(54) **RECHARGEABLE POWER IMPACT
WRENCH**

(75) Inventor: **Yuji Yamamoto**, Anjo (JP)

(73) Assignee: **Makita Corporation**, Anjo (JP)

(**) Term: **14 Years**

(21) Appl. No.: **29/287,923**

(22) Filed: **Oct. 2, 2007**

(30) **Foreign Application Priority Data**

Apr. 3, 2007 (JP) 2007-08734

(51) **LOC (8) Cl.** **08-05**

(52) **U.S. Cl.** **D8/68**

(57) **CLAIM**

The ornamental design for a rechargeable power impact wrench, as shown and described.

DESCRIPTION

FIG. 1 is a perspective view of a rechargeable power impact wrench showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
